UNITED STATES PATENT OFFICE.

ADDISON G. WATERHOUSE AND BENJAMIN B. BREWER, OF SACRAMENTO,
CALIFORNIA.

STEAM AND AIR ENGINE.

SPECIFICATION forming part of Letters Patent No. 232,158, dated September 14, 1880.

Application filed October 8, 1879.

To all whom it may concern:

Be it known that we, ADDISON G. WATERHOUSE and BENJAMIN B. BREWER, both of the city of Sacramento, State of California, 5 have invented a new and useful Improvement in Steam and Air Engines, of which the following is a specification.

The invention primarily relates to single-acting engines, or that class of engines in which 10 steam is admitted only on one side of the piston; and it consists in the general construction of the engine in combination with the form of constructing the valve and the method of connecting the same to the engine, together with 15 the manner of working the valve.

In the accompanying drawings, Figure 1 shows a sectional elevation of an engine and valve embodying our invention. Fig. 2 is a side elevation of the same. Fig. 3 is a rear elevation. Fig. 4 is a detail of the valve and chamber.

Fig. 1 shows a sectional elevation of the engine and valve, in which *m* is the crank; *n*, the connecting-rod; *S*, the piston, made long and 25 cup-like, so as to present a large surface for wear and to guide it in the cylinder *C*. The lower part of the piston is provided with annular grooves for packing, and the rod *n* is hung to the piston by the pin *i*. The valve 30 *H* is provided with two ports—the steam-port *C'* and the exhaust-port *b*—the steam entering into the valve-chamber through the pipe *d*. The valve *v* is of the form known as “rolling” valve. The steam enters and presses on the 35 top of the valve, and by its oscillation the steam is alternately let in the cylinder *C* and out through the exhaust-port *b*. The working of the valve will be described hereinafter.

Fig. 2 is a side elevation of the engine, showing the crank *m*, rod *n*, cylinder *C*, and valve *H*, also the eccentric *E*, which works the pump-rod *f*, the pump *P* being used as a feed-pump for the boiler. In this case we attach to the rod *r* a sleeve, *h*, which moves with the rod, 40 and connected to said sleeve *h* is the valve-rod *k*, which connects to the arm *o*, and gives the oscillating movement to the valve. In the valve-chamber *H* the rod *r* is connected to the eccentric *E* at a point, *e*, close to said eccentric, and the rod is guided by the bearing *g*, 45

which allows its longitudinal motion and prevents any side play.

The advantage of having the connection *e* close to the eccentric *E* is shown by reference to Fig. 3, which is a rear elevation of the engine, 55 showing the pump *P*, pump-rod *f*, guide-bearing *g*, connection *e*, and eccentric *E*, which causes an even reciprocation to the rod *f*—that is, while the eccentric is turning its upper center it causes the rod *f* to move comparatively slowly, and while the eccentric is turning on its lower center or close to the bearing *g*, it passes the center quickly, causing a comparatively quick motion on the rod on passing its lower center. This inequality to 60 the motion of the rod and eccentric we use to advantage, as follows: by connecting the valve-rod *k*, which oscillates the arm *o* and valve within the chamber *H*, to the pump-rod *f* at *h* by a collar or bearing; or, if desired, the 65 rod *k* can be connected directly to the eccentric *E*. In either case the uneven motion of *E* will be imparted to the arm *o* and valve, so at the quick end of the stroke the steam-port will be opened and closed quickly, so as to shut 70 off the steam while the engine is making but a small part of its stroke, thus using the steam expansively, while at the slow end of the stroke the exhaust is opened and moves slowly 75 in order to give plenty of time for the exhaust- 80 steam to escape.

By reference to Fig. 1 it will be seen that the valve-chamber *H* is made separate, and is screwed into the cylinder *C* by having the outer part of the steam-port *C'* threaded and 85 tightly screwed into *C*, as shown; or, if desired, the chamber *H* can be flanged and bolted to the engine-cylinder.

By reference to Fig. 4 will be seen a sectional view of the valve-chamber *H*, valve *v*, 90 rocking arm *u*, steam-pipe *d*, steam-port *C'*, and exhaust-port *b*. The valve *v* has steam-pressure on top of it that enters through the pipe *d*, and the valve is worked by the oscillation of the flattened arm *u*, so that as the 95 valve is at one end of the stroke, as shown in cross-lines, the exhaust-steam is free to pass out from port *C'*, and down through the exhaust-port *b*, and while the valve is at the other end of the stroke, as shown in dotted 100

lines, the steam passes through the chamber H and the port C' into the cylinder C, as shown in Fig. 1, while at the same time the exhaust-port b is closed. The arm u, that works 5 the valve, is made flat where the valve is fixed to it, and made round where it extends out of the chamber H and is connected to the arm or lever o.

What we claim as our invention is—
10 1. The separately-constructed two-ported valve H, provided with exhaust-pipe b, steam-pipe d, and boss C', by which the valve is screwed to or connected to the engine, and through which passes the steam communication 15 between the valve and the engine, in com-

bination with a single-acting engine, all constructed substantially as and for the purposes set forth.

2. The combination of the eccentric E, short connection e, guide-bearing g, pump-rod f, and 20 pump P with the rod k, arm o, separate valve-chamber H, and single-acting engine C, all arranged substantially as and for the purposes set forth.
